MUSIC LEAF TURNER

Filed July 6, 1923

2 Sheets-Sheet 2

UNITED STATES PATENT OFFICE.

THOMAS G. MARSHALL, OF NASHVILLE, TENNESSEE.

MUSIC-LEAF TURNER.

Application filed July 6, 1923. Serial No. 649,824.

To all whom it may concern:

Be it known that I, THOMAS G. MARSHALL, a citizen of the United States, residing at Nashville, in the county of Davidson, State 5 of Tennessee, have invented certain new and useful Improvements in Music-Leaf Turners; and I do hereby declare the following to be a full, clear, and exact description of the invention, such as will enable others skilled 10 in the art to which it appertains to make and use the same.

The present invention relates to new and useful improvements in music leaf turners, and more particularly to that type wherein 15 there is provided a main frame adapted to support a book or body of leaves to be turned, and a plurality of turning frames adapted to carry the individual leaves and movable from side to side of the main frame. 20 It is the general object of the invention to simplify and otherwise improve the structure, and to increase the efficiency and the readiness of attachment and operation of devices of this character.

It is more particularly an object of the invention to provide an improved actuating means for the turning frames, whereby they may be readily turned from one side to the other, of the main supporting frame, 25 and operable either by hand or by the foot of the player.

A still further object is to provide a device of this character wherein an operating or carrier arm is provided for moving the 30 leaf turning frames to the right or left, for the purpose of turning the pages forwardly and backwardly, said carrier arm being operable by a single lever, in the same direction, means being provided for 35 engaging the carrier arm to regulate the same as to its forward or returning action on the leaf turning frames.

Other objects and advantages will be apparent from the following description when 40 taken in connection with the accompanying drawings.

In the drawings:

Figure 1 is a front elevation of the device. 45 Figure 2 is a horizontal sectional view on the line 2-2 of Figure 1, taken just above the cam members, and showing the

flexible end of the carrier engaging the outer end of the cam member.

Figure 3 is an end view of the device, a 55 portion of a piano being shown in section.

Figure 4 is a perspective view of one of the cam members and the flexible end of the carrier.

Referring particularly to the accompanying drawings, there is shown a rectangular frame including the top and bottom rails 10 and 11, and the vertical end rails 12 and 13, the same being suitably connected together at the corners of the frame. Secured to and 60 extending between the upper portions of the end rails 12 and 13, is a bar 14, and pivotally mounted on this bar, adjacent the rail 13, is an angle or bell-crank lever 15, one arm of which has a link 16 connected thereto, while the other arm extends to a point 65 slightly above the top rail 10, and has a shorter link 17 connected thereto. Carried by the upper rail 10, and extending vertically thereabove, are two guides 18, and 70 slidably in these guides is a rack bar 19, one end being connected to link 17, and the other end being connected to the end of a coil spring 19', which is anchored to the top rail 10, adjacent the end rail 12. Dis- 75 posed between the guides 18, and extending from the front face of the top rail 10, to which it is secured, is a bracket 20, and rotatably supported in this bracket is a vertical shaft 21, carrying on its upper end a 80 gear 22 which meshes with the teeth of the rack bar 19. Projecting horizontally from the lower edge of the lower rail 11 is a ledge or shelf 23. Secured to and depending from the center of the lower face of this shelf is 85 a bracket 24, which pivotally supports a lever 25, extending forwardly and rearwardly of the said shelf. To the rear end of this lever 25 is connected the other or lower end of the link 16, and to the forward end 90 of the lever is pivotally connected a bent arm 26. To the free end of the arm 26 is connected a rod or wire 28, to which reference 95 will be made later herein. Rotatably supported in and extending between the ledges 100 23 and 27, is a vertical shaft 29. A plurality of angular U-shaped leaf turning frames 30 have the outer ends of their arms formed with the eyes 31 which are rotatably sup-

ported on the said shafts 21 and 29 for turning movement toward the right and left sides of the main frame, to carry the leaves of music forward and backward, as will be readily understood. Extending vertically between the arms of the frames 30 are the leaf engaging strips 32.

Secured to and extending forwardly from the intermediate portions of the end rails 12 and 13, are the brackets 33, and pivotally supported on these brackets, and extending forwardly and horizontally, are the arms 34 and 35, respectively. The outer end of each arm 34 and 35 is formed with a vertical flange 36, forming a cam element which curves in eccentric relation to the pivotal mounting of the carrier arm, and also of the frames 30. Carried by the rails 12 and 13, and extending forwardly therefrom, inwardly of the arms 34 and 35, are the bifurcated arms 38, and secured to each arm, and extending into the bifurcation thereof, is a spring elbow 39, which is flexed by the bight of each leaf turning frame, as it passes said elbow and is retained thereby.

Rigidly carried by the upper end of the shaft 21, is the L-shaped carrier arm 40, the depending or vertical leg 40' of which is provided with a flexible arm or finger 41, arranged to engage with the cam surfaces 36 of the arms 34 and 35, as the arm 40 reaches either side of the main frame of the device. Formed on the flexible finger 41 is a horizontal inwardly projecting lug or projection 42 which is arranged to engage behind the bight portions of the frames 30, successively, so that when the arm 40 is moved on its pivot this projection will carry the frame 30 over to the left-hand side of the main frame, together with the music leaf engaged thereby. Each of the arms 34 and 35 has an extension 43 disposed rearwardly of the main frame, and extending longitudinally of the rear of the frame, and pivotally connected at its ends to these extensions is a rod 44. Carried by the intermediate portion of this rod is a vertically disposed bifurcated member 45. Rotatably supported on the lower face of the shelf 23, is a forwardly and rearwardly extending shaft 46, the rear end of which is turned upwardly, as at 47, with the terminal of said portion directed rearwardly and engaged in the bifurcation of the member 45. The forward end of the shaft 46 has a radially extending arm 48 to which is connected a downwardly extending rod or wire 49. The wire 49, and the wire 28, are arranged to be passed between the keys of a piano, on which the invention is adapted to be secured. The rear face of the main frame is provided with brackets 50 for attachment to the music rest board of a piano, as will be readily understood. Small holes 65 are, of course, cut in the bottom wall of the

piano frame, below the keys, for the wires 28 and 49, the lower ends of said wires being connected with pedals 52 and 51, respectively, arranged on the floor, and adapted to be depressed by the feet of the player. 70

On the upper face of the forward end of the arm 35, inwardly and concentric with the vertical flange or cam element 36 thereof, is a second flange or cam element 36', which is engaged by the lower end portion of the 75 flexible finger 41 so that the said finger will be flexed sufficiently to permit the projection thereof getting behind a frame 30. This is particularly useful when the turning carrier arm 40 is being operated to return the frames 30 to their normal right-hand position, on the main frame. Such a construction prevents the arm 40 from carrying the frame back, when said arm is returning for another frame, at the left-hand side of the frame. 85

It will be readily seen that upon depressing the pedal 52 the lever 25 will be rocked causing the bell-crank 15 to draw the rack bar 19 toward the right, and turning the gear 22, which rotates the shaft 21, causing the arm 40 to be swung from its position at the right-hand side of the frame, to the left-hand-side, carrying with it one of the frames 30. When the frame 30 is carried to the left side of the main frame it will pass or snap in front of the spring elbow 39, and be retained thereby, together with the music leaf. As the pedal is released, the spring 19' will draw the rack bar 19 100 back toward the left, causing the arm 40 to swing over to the right side of the main frame. As the arm 40 approaches the right side of the frame, the lower end of its spring finger 41 will engage with the outer face of 105 the flange or cam element 36, which will cause the finger to flex outwardly, until it has reached a position where its projection 42 stands opposite the space between the vertical bight portions of the two outer frames 30, when the end of the finger will snap from the far end of the flange or cam element permitting the finger to move inwardly and dispose its projection 42 behind the outermost of the frames 30, ready 110 to carry this frame over to the left, when the pedal 52 is again depressed. 115

Should the player desire to repeat a page, it becomes necessary to return the page to the right side of the frame, and to accomplish this the player depresses the pedal 51, which rocks the shaft 46, and shifts the rod 44 toward the left, which results in the rocking of the arms 34 and 35 toward the right, simultaneously. The inner flange or 120 cam element 36' engages with the lower end of the finger 41 and withdraws the projection 42 from behind the frame 30 which is outermost at the right side of the frame. Then upon depressing the pedal 52, the arm 125 130

40 will be moved toward the left, and its finger 41 engage with the flange or cam element 36 of the arm 34, and cause the projection to snap in behind the frame 5 carrying the page or leaf to be re-turned. Upon releasing the pedal 52, the spring 19' will move the arm 40 to the right carrying the frame 30 with it, and engaging the frame with the other spring elbow, the 10 pedal 51 having been released almost simultaneously with the pedal 52.

Carried by each of the end rails 12 and 13 is an inwardly directed, and movable arm 53 which is adapted to engage with the back 15 portions of a book, which rests on the ledge 27, to hold the book in proper position, while permitting the leaves of the book to be free for turning.

Also carried by the front face of each of 20 the rails 12 and 13, is a forwardly extending L-shaped spring arm 54, which bears against the innermost of the turning frames, to normally urge them forwardly against the retaining spring 39, where each turning 25 frame will be held in proper position for engagement therebehind of the spring finger 42.

On the shaft 46 is a coil spring 55, one arm of which engages with the arm 47, while 30 the other end engages with the lower rail 11, to normally urge the shaft into normal position, that is with the cam members at the right of the device in position for engagement by the turning member to grip and 35 turn the leaves forwardly. This spring is necessary at this point because of the fact that the wire 49 being of such small diameter as to readily pass between the keys of the piano, the spring beneath the pedal 51 40 would have no upward pushing effect thereon. The frames 30 are made of a length to engage and turn the maximum sized page, but when smaller pages are to be turned the strips 30', which extend between the horizontal arms of the frames are slipped along 45 said arms to lie directly behind the pages.

What is claimed is:

1. A music leaf turner including a main frame, leaf turning frames on the main frame, means for holding the turning frames releasably at one side of the main frame, a carrier arm mounted on the main frame for swinging movement from one side thereof to the other, cam means on opposite sides of the main frame, a flexible finger on the carrier arm provided with a leaf turning frame engaging projection and arranged to engage and be flexed by the said cam means for disposing the projection in engagement with a leaf turning frame, and means for shifting the cam means whereby the flexible finger will be disengaged from a leaf turning frame at one side of the main

frame and reengaged with a previously moved turning frame at the other side of 65 said main frame, and means for restoring the carrier arm and said previously moved turning frame to normal position.

2. A music leaf turner including a main frame, leaf turning frames pivotally supported thereon, a pivoted arm for transferring the turning frames from one side of the main frame to the other, a pair of cam members movably mounted on the opposite sides of the main frame, a flexible member 70 on the said pivoted arm arranged to be normally engaged and flexed by one of the cam members, a projection on the flexible member arranged to be inserted between adjacent turning frames by the action of said 75 cam on the flexible member, and means for shifting the cam members to cause the other cam to engage the flexible member and dispose the projection thereof in engagement with a previously turned frame for returning 80 said frame to its original position.

3. A music leaf turner including a main frame, leaf turning arms on the frame, a carrier arm mounted on the frame for engagement with the turning arms to turn the 90 latter from one side of the frame to the other, operatively connected cams at opposite sides of the frame, means for shifting the cams to dispose them in the path of the carrier arm whereby to engage the turning arms at one 95 side of the frame and to release them at the other side, and another cam at one side of the frame and shiftable with the first cams to disengage the carrier arm from the turning arms at said first side and then reengage 100 said carrier arm with the turning arms at said other side.

4. A music leaf turner including a main frame, leaf turning arms on the frame, a carrier arm movable into engagement with 105 the turning arms for swinging the latter from one side of the frame to the other, a single cam at one side of the frame, a pair of cams at the other side of the frame, connections between the first and second cams 110 whereby said cams are shiftable to cause cooperation of the single cam successively with each of the said pair of cams to engage the carrier arm successively with the leaf turning arms at one side of the frame and to release said turning arms at the other side 115 of the frame, at times, and at other times to engage the carrier arm with the turning arms at said second side of the frame and release the carrier arm at said first side. 120

In testimony whereof, I affix my signature in the presence of two witnesses.

THOMAS G. MARSHALL.
